United States Patent Office.

EDWARD AUGUSTUS SWAIN, OF NEW YORK, N. Y.

Letters Patent No. 98,720, dated January 11, 1870.

IMPROVEMENT IN ADDING-MACHINE.

The Schedule referred to in these Letters Patent and making part of the same.

I, EDWARD AUGUSTUS SWAIN, of the city, county, and State of New York, have invented an Improved Adding-Machine, and do hereby describe the same.

Nature and Objects of the Invention.

The subject of my invention is an apparatus for use in adding up columns of figures in ledgers, &c., to enable said operation to be performed with greater rapidity and accuracy. It is of that class or description of such devices in which a series of parallel disks or wheels, suitably connected, and enclosed in a suitable case, constitutes the counting and registering-mechanism.

The improvement consists in a novel construction of carrying-mechanism, for connecting the disks.

Description of Drawings.

In the accompanying drawings, made a part of this specification—

Figure 1 is a front elevation, partly in vertical section, of an adding-machine embodying my improvements;

Figure 2, a vertical transverse section on the line *z*, fig. 1;

Figure 3, a vertical transverse section on the line *y*, fig. 1; and

Figure 4, a diagram illustrating the construction of the disks.

General Description.

The case *A* of my improved machine is in the form of a horizontal cylinder, and is provided with a flange or base, *B*, for its support.

It may or may not have a removable end, *a*, or its equivalent, to give access to the works.

A shaft, *C*, held in the end of the case by square ends *c*, or their equivalent, supports the disks *D*, which are mounted loosely thereon, at proper distance apart, and held from lateral displacement by collars *c'*, or their equivalent.

The disks *D* are constructed with peripheries sufficiently broad to receive, in parallel circumferential series, the indicating-figures *d* and holes or indentations *d'*, by which to rotate them, with which they are thus provided, as represented.

The circumference being suitably spaced, six or more series (of 1 to 0) of indicating-figures may be employed on each disk.

An engaging-hole or indentation is employed for each figure, being arranged in line laterally with it.

The case *A* is provided correspondingly with the several disks, in convenient position in its circumference, and opposite or over the series of engaging-holes or indentations *d'* in the disks, with slots *a'*, ten or more (preferably eleven) spaces in length, through

which to operate the disk; and, at proper relative distance from the lower ends of said slots, with a longitudinal slot, *a''*, a single space in width, or a corresponding provision for the exposure of the indicating-figures *d*, to enable the amount to be read.

The slots *a'*, for the exposure of the engaging-holes or indentations in the disks, being eleven spaces long, and provided, at their upper extremity, with offsets *a''*, for the exposure of the figures *d* at this point, or the holes or indentations *d'*, paralleled with the ciphers, so marked as to obviate the necessity for this latter provision, this preferable point is utilized for setting the disks by.

The lower extremities of said slots are at such relative distance from the sum-opening *a'*, as that corresponding figures to those presented there occur here.

Said slots and opening are, preferably, so disposed as to bring the latter within the base, as represented, in order to conceal the amount until the computation is completed.

A scale or series of figures, *a'''*, (running from 0 to 9,) bordering each of the slots *a'*, and spaced correspondingly with the figures and engaging-holes or indentations in the disks, serves to indicate the height of the exposed holes or indentations from the lower end of the slots.

For "carrying" the respective disks, except the last, they are provided, on their left sides, with projecting pins or tappets *d''*, corresponding with the ciphers on their peripheries, and in line therewith, (as indicated in fig. 4,) being arranged in a concentric annular series, and the respective ones, except the first, on their right-hand sides, with concentric ratchet-wheels *d''*, having teeth corresponding in number with the spaces on their peripheries, and a lever, *E*, adapted to engage with said tappets and ratchet-wheels, is pivoted transversely of the disk supporting shaft *C* between each two of the disks.

Said parts are so constructed and proportioned as that at each impulse of a lever, by the passage of a tappet on a disk to the right, a movement of one space shall be imparted to the disk to the left.

The levers being properly arranged, relatively to the registering-slot, the tens are thus accurately carried.

The normal position of the carrying-levers *E* is determined by means of stops *f*, and they are returned thereto by means of suitably-applied springs *g*.

Their construction is variable. They may be supported from longitudinal displacement by shoulders and collars, and their shoulders, for engagement with their stops *f*, be formed by transverse pins, as represented.

Their impulse-arms *e* may project rigidly therefrom, being attached to them, or made in one therewith.

Their arms *e*, for engagement with the ratchet-

wheels d'' on the disks to the right, may be adapted to rise, so as to pass over the teeth of the ratchet-wheels, as required, by being composed, wholly or in part, of flat springs, arranged edgewise to their path, as represented, or in other suitable manner.

Ratchet-wheels h , on the disk-supporting shaft C, engaged by spring-pawls i on the disks, prevent retrograde movement of the disks, and hold them from disarrangement.

To adapt the machine to indicate the lines counted, the base B of the case is constructed with a projecting straight front edge, b , to serve as a guide.

My improved carrying-mechanism combines compactness with superior efficiency, and adapts a larger number of periods of registering figures on the respective disks to be employed, thus increasing the capacity of a machine of a given number of disks, and facilitating their movement by shortening the path required to be traversed by the propelling-instrument.

Operation.

The operation of the machine is as follows:

The disks D are all at first set at 0, which may be most readily done by observing the openings a'' , provided in the case for this purpose, and turning the disks until ciphers in their series of figures d appear in them, when ciphers will also be at the lower extremities of the engaging-slots a' and in the registering-opening a'' and the tappets d'' , on the disks next the engaging-arms e of the carrying-levers E, be nine spaces removed therefrom.

Any number of figures, within the capacity of the machine, may now be counted, by simply turning the disks corresponding with the column in which the respective figures occur, a corresponding number of spaces, when the amount will appear in the registering-slot a' , the tens counted by each disk having been carried by the mechanism d'' d'' E, connecting the disks.

To enable a proper operation of the disks, the engaging-slots a' and their marginal scales a''' , in conjunction with the engaging-holes or indentations d' , in the peripheries of the disks, are provided.

Corresponding ones of the registering-figures d , on the peripheries of the disks, being at the bottoms of the engaging-slots a' and in the registering-slot a'' , it will be apparent that by turning a disk until the figure to be counted is there, a similar figure will also appear in the registering-slot, and that by continuing to turn it a number of spaces corresponding with the figures to be added, the tens being "carried" to the next disk, and by it in similar manner registered, the sum will finally appear.

The scales a''' facilitate engagement with the disks at the proper points.

The disks are propelled by a suitable pointed instrument, one of which may accompany each machine.

The holes or indentations d' in the peripheries of the disks are engaged by this, and by its movement until arrested by the bottom of the engaging-slot, the figure represented by the hole engaged with is counted.

The machine being set on the book or paper on which the figures are, across the columns, and successively moved down to the line being added, the place is thus kept.

As illustrating the process of counting, supposing the first two lines of a ledger-account to be 2,791.50 and 91.18. The disks being at 0, commencing at the right-hand figure of the upper line, 0 is found, at which the corresponding disk already stands. Taking the next, (5,) the engaging-hole d' , in the second disk opposite 5, in the scale a''' on the case, is engaged with, by means of the propelling-instrument, and the disk thereby turned, until arrested by the instrument coming in contact with the bottom of the slot a' , through which, introduced when the instrument is withdrawn, a figure, 5, in the registering-figures d , on said second disk, having been brought into the registering-slot a'' . The third, fourth, fifth, and sixth disks are now engaged with at 1, 9, 7, and 2, respectively, when the registering-slot will show 279150.

Taking now the second line, the first four disks, by engagement, respectively, at the holes in the line, with 8, 1, 1, and 9, are turned until the propelling-instrument is stopped, as before, when in the registering-slot will be found the sum of the two lines, viz, 288268; of the 18 added by the fourth disk, the ten having been carried to the fifth, by the engagement of one of the tappets d'' , on the side of the former, with the adjoining arm e of the carrying-lever E, on the second 0, occurring in that number of spaces, confining opposite the registering-slot.

It is proposed, by modification, to adapt the machine for counting sterling.

Claim.

I claim, as my invention—

The combination, with the disks or wheels D D of a counting-machine, operating substantially as herein described, of the tappets d'' , ratchet-wheels d''' , and carrying-levers E, constructed and arranged to operate as set forth.

To the above specification of my adding-machine, I have signed my hand, this 3d day of August, A. D. 1869.

EDWARD AUGUSTUS SWAIN.
